(57) **CLAIM**

The ornamental design of a tank, as shown and described.

DESCRIPTION

FIG. 1 is a right frontal upper perspective view of a tank that shows an embodiment of the new design.

FIG. 2 is a left frontal upper perspective view of the model represented in FIG. 1.

FIG. 3 is a right rear upper perspective view of the model represented in FIG. 1.

FIG. 4 is a left rear upper perspective view of the model represented in FIG. 1.

FIG. 5 is a right side view of the model represented in FIG. 1.

FIG. 6 is a left side view of the model represented in FIG. 1.

FIG. 7 is a frontal view of the model represented in FIG. 1.

FIG. 8 is a rear view of the model of FIG. 1.

FIG. 9 is a frontal view in vertical section of the model of FIG. 7.

FIG. 10 is an upper view of the model of FIG. 1.

The bottom of the tank can be flat and unornamented.

FIG. 11 is a right upper frontal perspective view of the model of FIG. 1, showing the optional attachment to a lid.

FIG. 12 is frontal view of the model of FIG. 1, showing the optional attachment to the lid. The right, left, and rear views of the lid are identical. The bottom of the lid can be flat and unornamented; and,

FIG. 13 is an upper view of the model of tank shown in FIG. 12.
